CLAIM

The ornamental design for a book light, as shown and described.

DESCRIPTION

FIG. 1 is a front, top perspective view of a book light, showing our, new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail “9” identified in FIG. 1;

FIG. 10 is an exploded view thereof; and,

FIG. 11 is another perspective view thereof, shown in an alternative position.

The dashed lines in the figures illustrate portions of the book light, that form no part of the claimed design. The dash dot dash lines in FIGS. 1 and 9 are for the purpose of illustrating the enlarged view indicators and fount no part of the claimed design.

1 Claim, 11 Drawing Sheets
